UNITED STATES PATENT OFFICE.

HENRY B. DE CAN, OF ST. MARIES, IDAHO.

STOVE.

Application filed June 30, 1927, Serial No. 202,641. Renewed May 29, 1928.

This invention relates to stoves, and particularly to that class of stoves having a hot air pipe extending through the stove and opening below the stove for the inlet of cool air and an opening above the stove for the outlet of warm air.

The general object of my invention is to improve the construction of the class described by the provision of means whereby the air entering the air pipe will not be immediately subjected to intense heat but that the air pipe will be highly heated around its upper portion to thus secure a much better upward draft of air than is possible where the heat is applied at the lower end of the air pipe.

A further object is to provide a stove of this character having a fire box and grate, the grate being so constructed as to carry relatively cool air to an air space or chamber surrounding the lower portion of the air pipe so as to keep this lower portion of the air pipe relatively cool.

Other objects will appear in the course of the following description.

My invention is illustrated in the accompanying drawing, wherein:—

Figure 1 is a longitudinal vertical sectional view of a stove constructed in accordance with my invention;

Figure 2 is a section on the line 2—2 of Figure 1;

Figure 3 is a fragmentary section on the line 3—3 of Figure 1;

Referring to these drawings, 10 designates a stove, which may be of any suitable form or construction and which may be of cast iron, sheet iron or of any other suitable material. I have illustrated this stove as being relatively elongated horizontally and provided at its rear end with the flue 13. A grate extends longitudinally across the stove and divides the fire space 14 of the stove from the ash space 15. This grate preferably consists of three parts, a central oscillatable, rotatable grate bar 16, which is preferably cylindrical and opens at its forward end upon the front of the stove and constitutes a fresh air duct, and the lateral grate bars 17 which are flat.

These flat grate bars 17 may have openings therethrough of any desired shape and these grate bars may be either fixed in place or oscillatably mounted. The cylindrical grate bar 16 is hollow to provide an air duct, as previously stated, and is formed with outstanding fins or lugs so that as this cylind-

rical grate bar is oscillated the fuel will be dislodged and shaken and if sufficient oscillation is given to the grate bar, the burned coals may be thrown over upon the grate bars 17, permitting the stove to be dumped.

The grate bars 16 and 17 at their rear ends are supported upon a transversely extending wall 18 by means of a gudgeon 19 of any suitable construction entering a bearing opening in said wall. The wall 18 forms the front wall of an air chamber 20, the front wall 18 of this air chamber extending upward from the bottom of the stove to a distance above the grate bars, and the top of the air chamber being formed by the wall 21 which is shown as apertured. The front wall 18 is formed with apertures 18^a which are in alignment with the hollow or tubular grate bar 16, and inasmuch as this grate bar 16 is open at its rear end, air entering the air duct formed by the tubular grate bar 16 will be discharged into the air chamber 20 through the openings 18^a in any rotated position of the grate bar 16.

Extending upward through this air chamber 20, through the top 21 and through the top of the stove is the air pipe 22 which extends below the bottom of the stove and extends to any desired height above the top of the stove and is supported in any desired manner as, for instance, by flanges 23 formed upon the air pipe 22 and resting upon the bottom of the stove. This air pipe 22 is preferably, though not necessarily, semi-circular in cross section and the wall of this pipe may be formed by the end wall of the stove if desired, though I do not wish to limit myself to this. The object of this air pipe 22 is to carry the air of lower temperature adjacent the floor upward through the stove and discharge the warmer air near the ceiling of the room. The heat of the fire in the stove will cause a draft or air current in the cold air pipe that will draw the air from the floor and carry it through the air pipe and cause a constant circulation of air to thereby cause the air in the room to be maintained at a more or less uniform temperature.

In order to secure an upward draft of air through the air pipe, it is necessary that the lower portion of the air pipe be surrounded by relatively cool air, and it is for this purpose that I have provided the cool air chamber 20, as I have found in actual practice that if the lower portion of the pipe is highly heated, warmer air tends to escape at the lower portion of the pipe and not at the top

and there will not be the draft which is desired. With my construction above the upward draft is greater than if the heat were applied at the lower end of the air pipe. The 5 cylindrical grate section, it will be seen, constitutes a duct whereby cooler air is constantly carried into the air chamber 20. The air pipe 22 may be made of cast iron or sheet iron and, as before remarked, may be of any 10 suitable construction or form and supported in any suitable manner within the stove.

As shown in Figure 1, the back wall of the stove is provided with an opening 24 disposed slightly above the adjacent end of the hollow 15 or tubular grate 16 and communicating with the interior of the air chamber 20. Air enters the front end of the cylindrical grate bar 16 and passes back through this grate bar and through the openings 18 into the chamber 20 and then out through the opening 24. Without this opening 24, the air would enter the chamber 18 and become dead and there would be no circulation. This structure provides a connecting link, as it may be called, 25 between the cold air draft and the grate, as the air passing around the lower end of the pipe 22 and going out through the opening 24 tends to keep the cold air pipe cooler at the lower end and thus secures a better circulation of the air in the room.

It is also to be understood that I do not wish to limit myself to any particular form of stove nor to the details illustrated, as these 30 may be varied in many ways without departing from the spirit of the invention as defined in the appended claims.

I claim:—

1. A stove of the character described having an air chamber adjacent its rear end and 40 an air pipe extending upward through the bottom of the stove and through said air chamber and through the top of the stove, the air chamber terminating short of the top of the stove to permit products of combustion 45 to pass around the upper portion of the air pipe.

2. A stove of the character described having therein an air chamber extending upward

through the bottom of the stove and terminating short of the top of the stove, the stove 50 having a flue extending from the stove above the air chamber, and an air pipe open at its upper end and extending vertically through the stove and having its lower portion disposed within said air chamber.

3. A stove of the character described having an air chamber at its rear end having a front wall extending upward from the bottom of the stove and a top wall extending from the rear wall of the stove to the front wall of the air chamber, grate bars extending longitudinally from the front wall of the stove to the front wall of the air chamber to provide a fire space above the grate bars and an ash pit below the grate bars, said air chamber 60 extending above the grate bars, a cool air duct extending from the front of the stove beneath the fire space and opening into said air chamber, a flue extending from the top of the stove above the air chamber, and a cool air pipe extending vertically through the stove and projecting beyond the top and bottom of the stove and being open at its opposite ends, the lower portion of said pipe being disposed within said air chamber.

4. In a stove of the character described having an air chamber at the rear end of the stove, the air chamber being less in height than the height of the stove and having a front wall and a top wall, a grate extending 80 from the front wall of the stove to the front wall of the air chamber and comprising a plurality of grate bars, one of said bars being in the form of a hollow cylinder opening at its front end upon the front of the stove and at 85 its rear end into the air chamber, a flue extending from the stove at a point above the air chamber, and an air pipe extending vertically through the stove and projecting below the bottom of the stove and above the top 90 thereof and open at its ends, the lower portion of the air pipe being disposed within the air chamber.

In testimony whereof I hereunto affix my signature.

HENRY B. DE CAN.
